CIGARETTE EXTINGUISHER

Jay B. Hinson, Hartsdale, N. Y.

Application April 29, 1940, Serial No. 332,164

3 Claims. (Cl. 131—237)

My invention relates to cigarette extinguishers, the primary object of the invention being to make the proper disposition of a partially consumed cigarette or cigar so convenient that the improper disposition of such articles will disappear.

The invention aims to provide a cigarette extinguisher capable of extinguishing the burning end of the cigarette more quickly and with less effort than the prior devices which have been proposed for this purpose.

Another object of the invention is to provide a cigarette extinguishing mechanism which lends itself readily to combination in an ash tray.

Another object of the invention is to provide a cigarette extinguisher which can be carried conveniently in the pocket or in a woman's pocketbook or handbag.

Another object of the invention is to provide a cigarette extinguisher construction which is especially practical from the standpoint of cost of manufacture, the parts of the extinguisher mechanism being few in number and so constructed and arranged that the device can be made at an extremely low cost on account of its simplicity.

The invention will be understood from a consideration of the accompanying drawing which illustrates by way of example several embodiments thereof.

Referring now to the drawing:

Fig. 1 is a view in vertical section of an ash tray for table and desk use embodying my improved extinguisher;

Fig. 2 is a similar view of a modified form of such an ash tray embodying the invention;

Fig. 3 is a horizontal section looking upwardly on line 3—3 of Fig. 2;

Fig. 4 is a horizontal section taken higher up through the extinguishing mechanism shown in Fig. 2, but looking down;

Fig. 5 is a view in longitudinal section of a pocket type of extinguisher;

Fig. 6 is a transverse section taken on line 6—6 of Fig. 5;

Fig. 7 is a view similar to Fig. 5 of a modification;

Fig. 8 is a vertical section of a further modification intended for use in a motor vehicle;

Fig. 9 is a plan view of the extinguishing member shown in Fig. 1;

Fig. 10 is a vertical section of a modified form of extinguishing member and mounting;

Fig. 11 is a similar view of a further modification; and

Fig. 12 is a view of a detail of the construction shown in Fig. 11.

Referring now to the accompanying drawing, and first to the device shown in Fig. 1 the ash tray 1 here illustrated may be made of any suitable material, such, for example, as ceramic ware or a suitable molded plastic material, and comprises an annular shelf portion 2 and a central, preferably cylindrical recess 3 which is closed by 10 a dome-shaped member 4 resting upon lugs 5. The lower edge of dome-shaped member 4 is received below a shoulder 6 at the top of recess 3 so that a reasonably tight joint is provided for the purpose of excluding the free entrance of 15 air into the chamber 7 which is formed by dome-shaped member 4 and recess 3.

Member 4 is provided at the top with a cigarette-receiving aperture 8 having a diameter somewhat larger than that of a cigarette, it being 20 unnecessary that the cigarette fit the aperture closely. In the event a particular device is desired principally for extinguishing cigars, this aperture is made of suitable size to receive cigars, that is, a little larger than the average cigar. 25 Cigarettes may readily be extinguished in cigar extinguishers. It is somewhat more desirable, however, to have separate extinguishers available for both cigars and cigarettes or to provide dome-shaped member 4 with two apertures, one of each 30 size. These remarks apply not only to the form of my invention illustrated in Fig. 1, but also to the modifications to be presently described.

Cigarette-receiving aperture 8 is flared slightly at its mouth so as to facilitate the entrance of 35 the burning tip of the cigarette, and the length of this aperture or throat is such as to accommodate the length of the average cigarette stub or butt at the time it is discarded and permit its burning tip to be brought in contact with a 40 valve-like abrading member 9 having a relatively high central part with downwardly sloping sides, positioned at the inner end of aperture 8. Abrading member 9 is attached to the upper and small 45 end of a volute, or spiral, wire spring 10, the lower end of which is supported upon lugs 11 projecting inwardly from the walls of dome-shaped member 4. The abrading member 9 may be secured to spring 10 by winding one or more turns 50 of the spring wire at the center of the spiral tightly on the stem of member 9, or in any other convenient way, to prevent rotation of member 9. The friction of the outermost turn of the 55 spring on its supporting lugs is sufficient to prevent rotation of the spring.

In extinguishing a cigarette the cigarette stub S is inserted in aperture 8 and the burning tip is thrust against the valve-like abrading member 9, usually with sufficient pressure to force the member inwardly away from its seat, thus compressing spring 10 to a greater or less extent. The extinguishing motion may be merely a reciprocating motion, the cigarette stub being worked up and down, or it may be an oscillating motion produced by rolling the upper end of the cigarette stub between the fingers (usually between the thumb and first finger), or it may be a combination of these two motions. The mounting of abrading member 9 and spring 10, as previously explained, is such that the abrading member is held so as to resist the turning motion of the cigarette.

The walls of the aperture or mouth 8 guide the cigarette in such a way as to cause the central portion of the burning tip to engage the high central part of abrading member 9, producing disintegration of the tip by a combined expansive and abrasive action, the surface of abrading member 9 being roughened to a sufficient extent to exert a disintegrating action upon the ashes and burning material on the cigarette tip. The thrust or pressure of the stub on the valve-like abrading member forces it inwardly from its seat and opens a valve-like passageway between the abrading member and aperture 8 and permits the ashes and burning material to descend around the peripheral edges of the abrading member into the chamber 7 where they collect on the floor of recess 3. As soon as the combustion at the end of the stub is extinguished, without removing the fingers from the stub, it is lifted from the aperture 8 and placed on the shelf portion of the ash tray 1.

As soon as the pressure on the cigarette stub S is released, spring 10 returns valve-like tool 9 to its normal position as shown in Fig. 1, thus closing aperture 8. This accomplishes two things; first, the closing of aperture 8 prevents the escape of odors resulting from whatever combustion of the disintegrated material may take place within chamber 7; second, it prevents the entrance of fresh air from the outside into chamber 7 so that the combustion of the smoldering material ground from the burning end of the cigarette ceases due to the lack of combustion air and to the disintegrated state of the ground off material.

After a number of cigarettes have been extinguished in this way the collection of stubs on the shelf portion 2 may be brushed into the recess 3, using the dome-shaped member 4, or the pitch of shelf 2 may be made steep enough so that as soon as member 4 is lifted, the stubs will slide into the recess. The rim of ash tray 1 is provided with a series of pockets 12 in which lighted cigarettes may be rested before being completely consumed.

In Fig. 2 a modified form of cigarette extinguisher and ash tray is provided which comprises a tray 13 of metal or other suitable material having a removable bell 14 resting at the center, the tray 13 and bell 14 being of such shape that the lower edge of the bell fits fairly closely the surface of the tray, thereby forming a substantially closed chamber 15 within the bell. Secured at the upper end of bell member 14 there is a tubular member indicated generally by reference numeral 16 which is provided with a lower enlarged cylindrical portion 17 and an upper throat portion forming a cigarette-receiving

aperture 18, the two portions being connected together by a shoulder portion 19. These parts comprise a cigarette extinguisher mechanism of a sort similar to that described in connection with Fig. 1.

A tool 20 illustrated in detail in Fig. 4 is urged upwardly by means of a volute wire spring 21, the rim portion 22 of the tool preferably being smooth so as to constitute a valve which closes with a high degree of tightness against the shoulder 19. The surface of the central portion of the tool within the marginal portion 22 is provided with cutting teeth to remove the burning material from the end of the cigarette stub S in an extremely short and quick operation. Tool 20 is provided with a central depending stem as indicated in the drawings, similar to that of grinding member 9, to which the upper end of spring 21 is frictionally, or otherwise secured in such manner as to prevent its rotation when the cigarette stub is rotated in contact with it.

The lower end of spring 21 is supported upon a plurality of small projections 23 bent inwardly from the lower margin of the cylindrical portion 17 of tubular member 16. These are shown in bottom view in Fig. 3. The lower end portion 24 of spring 21 is preferably extended crosswise as shown in Fig. 2 and forms the support for a bell clapper 25, if one is desired.

The entire mechanism can be assembled within the tubular member 16 very quickly and by a very simple operation. The tool 20 and spring 21 having bell clapper 25 attached thereto are placed within the lower end of tubular member 16 and the lowermost coil of spring 21 is sprung past projections 23.

This extinguisher shown in Fig. 2 is used in substantially the same way as described in connection with Fig. 1. The tool 20 is smaller in diameter than the interior of the lower portion 17 of the tubular member so as to allow the disintegrated particles to descend around the edges of the grinding tool and then pass through the coils of spring 20 into chamber 15.

The securing of tubular member 16 at the central portion of the top of the bell, and the suspending of bell clapper 25 at the center of the lower end of tubular member 16 does not interfere with the vibration of the device to produce a ringing bell-like sound, and the flared upper end of throat 18 constitutes a convenient handle.

Referring now to Figs. 5 and 7, there are here illustrated two forms of my improved cigarette extinguisher which can be conveniently carried in the pocket or in a woman's pocketbook. Referring first to Fig. 5, this device comprises two telescoping tubular members 26 and 27 which, although illustrated as cylindrical, may be square, hexagonal or other desired shape in cross section. The lower portion 27 which forms the chamber for collecting the disintegrated material and ashes is frictionally held within the lower end of tubular member 26 and may be removed therefrom for cleaning.

The upper end of tubular member 26 is provided with a flared cigarette-receiving throat 28 similar to throat 18 of the form shown in Fig. 2, and in fact tubular member 26 is quite similar to tubular member 16, and the cigarette extinguishing mechanism is like that shown in Fig. 1 except that the volute spring 10a for supporting the abrading member 9a is somewhat smaller in diameter. In this form of my invention the spring 10a is seated upon a plurality of indentations 29 which are pressed inwardly from the

exterior surface of tubular member 26. The diameter of abrading member 9a is preferably such that this member and spring 10a can be inserted after the indentations 29 are formed, and the parts assembled by forcing the lower end of spring 10 past the indentations.

The modified form of extinguisher shown in Fig. 7 embodies some of the features of Fig. 5 and some of those of the device of Fig. 2. A tool 20 having milling type cutting teeth and a valve rim is employed. The volute spring 10b is supported by springing its lowermost coil into a circular recess formed by spinning a bead 30 in the wall of tubular member 26a. The bottom member 27a is telescoped on the outside of tubular member 26a, just the opposite to the form shown in Fig. 5, and bead 30 forms a stop for limiting the extent of the telescoping relationship.

It will be understood that the valve action of the abrading members in the pocket or pocketbook type of extinguisher shown in Figs. 5 and 7 is especially important from the standpoint of preventing the escape of ashes and blackened material from these chambers. This form of extinguisher also lends itself to incorporation in such other articles, either carried in the pocket or pocketbook such, for example, as cigarette cases, vanity cases, cigarette lighters and lipstick devices.

In Fig. 8 there is illustrated an adaptation of the cigarette extinguisher for automotive use. In the dash 31, or other convenient portion of the car, there is provided a chamber 32 in the bottom of which there is a removable drawer or tray 33. This chamber is closed by means of a cover 34 hinged at 35 and held closed by a spring latching mechanism 36. At a convenient place in this cover above tray 33 a cigarette extinguisher mechanism 37 is provided. As illustrated, this mechanism is of the kind illustrated in Fig. 2 comprising tubular member 16 in which the volute spring 21 is supported upon inwardly turned projections 23 at the inner end of the tubular member. The valve-like abrading member illustrated is, however, of the sort shown in Figs. 1 and 5 and indicated by number 9a.

Immediately below the cigarette extinguisher mechanism 37 cover member 34 is provided with an aperture 39 which is normally closed by a second valve-like member 38 biased to closed position by a spring 38a. Through this aperture the dead cigarette stubs after extinguishing may be dropped into the tray or drawer 33. The cigarette extinguishing device 37 constitutes the handle for opening cover member 34 for the purpose of emptying tray 33. The disintegrated material from the extinguishing mechanism 37 drops directly into tray 33 so that this tray receives both the ground off materials and the extinguished stubs.

By closing both the extinguishing mechanism aperture and the stub-receiving aperture 39 by means of resiliently biased valve members the escape of undesirable odors, dust and ashes is prevented; also outside air is excluded from chamber 32, making this a combustion suppressing chamber similar to the chambers of the other modifications.

Figure 9 represents the face of abrading members 9 and 9a shown in the devices of Figs. 1 and 5. This form of abrading member instead of having sharp teeth like member 20 is provided with rib-like protuberances which serve to grind off and disintegrate the burning material and ashes from the end of the cigarette. The aim is to provide

a surface which will not only remove the ashes and glowing ends of tobacco fibres, but also will remove enough of the hot portions of these fibres so that it will be impossible for the combustion to be re-established after the stub is removed from the cigarette-receiving aperture. Hence in the case of an automobile, for example, even though a smoker should throw the extinguished stub out of the car window instead of inserting it through aperture 39 into the tray 33, no roadside fire hazard would result.

In Fig. 10 there is illustrated a modified form of abrading member and spring mounting therefor in which the member 40, which may have any suitable surface as above described, is provided with an enlarged and preferably tapering lug or projection 41 on its lower side to facilitate mounting in the upper end of the particular form of spring illustrated in this figure. This spring has two volute portions 42 and 43 with their smaller ends adjoining one another, the upper volute portion 43 forming a pocket for the reception of the lug 41 of the abrading member.

In Figs. 11 and 12 a modified form of cigarette extinguisher is illustrated in which the thrust of the cigarette stub against the valve-like abrading member causes the member to rotate. In this device the cigarette extinguishing mechanism 44 comprises a tubular member having a contracted upper or throat portion 45 forming the cigarette-receiving aperture, and a lower flared portion 46 which forms the seat for the valve-like abrading member 47. From this lower portion four narrow legs project downwardly in substantially parallel relation. Two of these legs 48 are bent toward one another into horizontal position and their inner ends are notched as shown in Fig. 12 so as to together form an elongated opening 49 to receive slidably a stem 50 with which abrading tool 47 is provided.

This stem 50 is twisted as shown in Fig. 11 to provide a cam surface which coacts with the elongated opening 49 to cause the tool 47 to rotate back and forth, or oscillate, as it is moved first downwardly and then upwardly as the cigarette stub is worked up and down. A helical spring 51 normally holds the valve-like tool 47 in engagement with its seat so as to close the cigarette aperture. The other pair of legs 52 depending from the flared lower portion 46 are straight and serve together with the vertical portions of legs 48 as guides for the periphery of the tool 47 so as to cause the tool to slide easily in its up and down motion. The cigarette extinguishing mechanism 44 is secured to any desired chamber-forming member, such, for example, as dome-shaped member 53, by soldering, welding or otherwise, as indicated by numeral 54, along the periphery of its flared lower portion 46.

In operation an abrading action is exerted upon the burning tip of the cigarette without twisting the cigarette between the fingers, and the valve-like tool 47 repeatedly recedes from its seat allowing the disintegrated material from the burning tip to be forced, by the reciprocating motion of the stub, into chamber 55 within dome-shaped member 53. A few repetitions of this reciprocating movement of the cigarette stub extinguishes it and it then can be placed in the ash tray 56.

It will be understood that the valve passage is opened to permit the descent of the disintegrated material as soon as the rim of the valve-like abrading member 47 passes below the lower

edge 57 of the lower flared portion 46 of tubular member 45, which is held by open halves 52. In this form of ash tray the dome-shaped member 53 is held in central position on the tray member 56 by means of a plurality of upward projections 58 pressed into the bottom of the tray. In this way free access is permitted to the central portion of the tray so that the extinguished stubs from the outer portion of the tray can be brushed into the space below the dome-shaped member 53 as desired.

It will be understood that any of the forms of abrading members illustrated may be used in any of the various modifications of the extinguisher. The pitch of their surfaces is preferably such as to enable the ground off materials to move as freely as possible into the combustion-suppressing chamber.

The volute springs illustrated in the forms of the invention shown in Figs. 2, 5, 7 and 8 are desirable for simplicity and cheapness of construction and at the same time provide for the free entrance of the ground off materials from the abrading member through the lower part of the tubular member 16, 16a, 26 and 26a into the combustion-suppressing chambers below. The ground off particles can flow or pass freely in a longitudinal direction through the spaces between the horizontally as well as vertically separated coils of these springs. In addition since the coils of a volute spring decrease in diameter towards the apex, the spring becomes gradually stiffer towards the apex and this, together with the wide base at the bottom, gives the desired support and control of the valve-like abrading member. Also in the device shown in Fig. 1 the wide base of the volute spring enables it to be supported upon the comparatively short lugs 11 and this facilitates the manufacture of the dome-shaped member 4.

The cigarette-receiving aperture or throat in all forms of the extinguisher, such, for example, as the aperture 8 of the device of Fig. 1, should be enough larger in diameter than the size of the cigarette so as to permit and facilitate the free rotation or turning of the cigarette by rolling it between the fingers, that is to say, usually between the thumb and first finger, the surface of the aperture serving as a guide bearing to direct the end of the cigarette against the grinding member while exerting a minimum of frictional resistance to the rotation of the cigarette. The aperture may be considerably larger than the cigarette since, as soon as the operation of grinding off the burning materials is completed, the aperture is closed by the valve-acting abrading member.

The cigarette extinguishing mechanism of the present invention contains simple parts which are few in number and all can be manufactured readily and at low cost. The assembly of the mechanism is particularly simple and also contributes to low cost of manufacture. The mechanism furthermore lends itself readily to a combination with an ash tray without substantially altering its appearance. The dome-shaped member 4, for example, in the form shown in Fig. 1 is not unlike in appearance to the knob-like members provided in ash trays to be used for flicking off the ashes of cigarettes and for knocking

the cigarette butt from the cigarette. The dome-shaped member 4 can be easily removed from the cigarette extinguisher and can be used as a cigarette holder or cigarette flicker.

ing the ashes out of tobacco pipes. This dome member 4 can be used for such purposes if desired.

It will be understood that the above is an exemplifying disclosure of a number of embodiments of my invention and that various changes may be made without departing from the spirit and scope of the invention which is defined in the appended claims. It will also be understood that in these claims the term "cigarette" includes cigars and similar smokers' articles.

It will be further understood that any of the hollow members 4, 15 or 53 may be used with any suitable tray other than those illustrated in the drawing and that if desired such hollow member with its cigarette extinguishing mechanism may be considered as an article of manufacture distinct from the tray with which it is to be used.

I claim:

1. In a cigarette extinguisher, a chamber for receiving burning material from a lighted cigarette, said chamber having a mouth within which the burning tip of a cigarette may be inserted, a circular-valve-like abrading member normally closing said mouth and being resiliently mounted for movement bodily under the thrust of the cigarette to open said mouth and permit abraded material to enter said chamber, said abrading member having a relatively high central part with downwardly sloping sides and said mouth being arranged to guide the central portion of the cigarette tip into engagement with the high central part of the abrading member causing said tip to be expanded to aid in disintegrating the same.

2. In a cigarette extinguisher, a chamber for receiving burning material from a lighted cigarette, said chamber having a mouth within which

the burning tip of a cigarette may be inserted, a circular valve-like abrading member normally closing said mouth and being resiliently mounted for movement axially with respect to said mouth to open or close the same and yielding under the thrust of the cigarette to open position to permit material to enter said chamber, said abrading member having a relatively high central part with downwardly sloping sides and said mouth having walls positioned to guide the cigarette tip to cause the central portion of the burning tip to engage the high central part of the abrasive member thereby enabling the tip to be disintegrated by expansive and abrasive action.

3. In a cigarette extinguisher having a chamber for receiving burning material from a lighted cigarette, said chamber having a mouth within which the burning tip of a cigarette may be inserted, an abrading member having a roughened conical surface resiliently mounted for axial movement within said chamber and coacting with said mouth to close the same, the walls of said mouth being adapted to guide the cigarette into engagement with said abrading member, said member being adapted to remove material on the burning tip of the cigarette when it is engaged therewith and simultaneously yielding inwardly to admit the abraded material into the chamber.

JAY B. HINSON.
